UNITED STATES PATENT OFFICE.

RUE S. HESTAND, OF HOWE, TEXAS.

RATCHET DIE-STOCK.

1,310,620.

Specification of Letters Patent. Patented July 22, 1919.

Application filed February 10, 1919. Serial No. 275,981.

To all whom it may concern:

Be it known that I, RUE S. HESTAND, a citizen of the United States, residing at Howe, in the county of Grayson and State 5 of Texas, have invented certain new and useful Improvements in Ratchet Die-Stocks, of which the following is a specification.

My invention relates to ratchet die stocks, and more especially to that class de- 10 signed for threading pipe in close places, as down in a trench or against walls, be- 15 tween rafters, etc., and its novelty, adapta- 20 tion and many advantages will be fully understood from the following description 25 and claim, taken in conjunction with the an- 30 nected drawings wherein like numerals of 35 reference indicate corresponding parts, and 40 in which—

Figure 1 is a side view of a die stock em- 20 bodying my invention; Fig. 2 is a plan view 25 thereof, small portions being broken away 30 in both views to show more important fea- 35 tures; and Fig. 3 is a detail end view of 40 Fig. 1.

Referring to the drawings, 1 represents 25 ordinary threading dies, 2 the die stack, 3 and 4 die adjusting screws, 5 the usual 35 socket or sleeve for bushing 6, and 7 a thumb 40 screw for removably securing said bushing. 45 All of which are of well known construction 50 and require no extended description.

My improvement consists in adding a cir- 55 cular enlargement 8 to the outer end of the 60 socket 5, with ratchet teeth 9 formed around 65 its circumference; and also in providing a 70 similar socket 10, with ratchet teeth 11, upon 75 the opposite side of the stock 2. Housings 80 12 and 13 encircle the enlarged portions, 85 extend rearwardly and converge to connect 90 with a handle 14 which is formed integrally 95 with the housing 12, while 13 is secured to 100 the handle by rivet 15. Double-acting pawls 105 are pivoted upon pins 17, to the extended

inner sides of the housings 12 and 13 respec- 45 tively, and either of their free ends may 50 be brought into engagement with the ratchet 55 teeth 9 and 11 for turning the die stock for- 60 ward or back. To actively retain the pawls 65 in either operative position in relation to 70 the ratchet teeth when the handle 14 is os- 75 cillated, coiled springs 18, located in sock- 80 ets 19, carrying pintles 20 that engage 85 notches 21 in the enlarged hub of the pawls 90 are provided. Moving the toes of a pawl 95 from one position to the other, rocks the 100 notch 21, with its pintle, to a position above 105 or below the center of pin 17, when the ten- 110 sion of the expansion springs will respec- 115 tively, yieldingly retain either toe of the 120 pawl in engagement with the respective 125 ratchet teeth, enabling the turning of the 130 die stock in either direction, right or left 135 as desired.

It will be obvious that changes may be 140 made in the details of the construction and 145 configuration of the invention without de- 150 parting from the spirit thereof as defined 155 by the appended claim.

Having described my invention and set 160 forth its merits, what I claim as new, and 165 desire to secure by Letters Patent, is—

The combination with a socket-extended 170 die stock and a bushing located therein, of 175 a diametrical enlargement of the outward 180 projecting end of the socket, having trans- 185 versely disposed ratchet teeth surrounding 190 the face thereof, a similar socket extending 195 from the opposite side of the die holding 200 portion of the stock, housings encircling the 205 ratchet portions and connected with a han- 210 dle, and a double-acting pawl pivotally 215 mounted in each of the extended housing 220 portions for engaging the ratchet teeth.

In testimony whereof I affix my signature.

RUE S. HESTAND.
